LOAD TRANSFER DEVICE

Ray Cyrus Yeoman, Lufkin, Tex., assignor to
 Texas Foundries, Inc., Lufkin, Tex., a corpora-
 tion of Texas

Application March 28, 1945, Serial No. 585,237

6 Claims. (Cl. 94—8)

1

This invention relates to load transfer devices and more particularly to devices for transferring loads between adjacent slabs of concrete or the like.

One of the objects of the invention is to provide a load transfer device which is simple and inexpensive to manufacture and install and which will effectively transfer both vertical and horizontal loads between the slabs.

Another object is to provide a load transfer device which is resilient to yield horizontally under expansion and contraction of the slabs.

Still another object is to provide a load transfer device formed of wires or rods twisted together to transmit vertical loads between the slabs and to yield to permit relative horizontal movement of the slabs.

Still another object is to provide a load transfer device formed of a single sheet or plate having outwardly projecting leg portions to be imbedded in the slabs and a deformable central portion to accommodate relative horizontal movement of the slabs.

The above and other objects and advantages of the invention will be more readily apparent from the following description when read in connection with the accompanying drawing, in which—

Figure 1 is a partial vertical section through adjacent slabs connected by a load transfer device embodying the invention;

Figure 2 is a horizontal section through Figure 1;

Figure 3 is a view similar to Figure 1 of a slightly modified construction;

Figure 4 is a partial perspective section showing another construction;

Figure 5 is a view similar to Figure 1 showing an alternative form of load transfer device; and

Figure 6 is a partial perspective view of the load transfer device of Figure 5.

As shown in Figures 1 and 2, the load transfer device is adapted to connect adjacent slabs 10 and 11 of concrete or the like which are provided with a compressible filler strip 12 between the adjacent faces. The filler strip 12 may be of any desired compressible construction and is preferably formed with openings therethrough to accommodate the load transfer devices.

The load transfer devices of Figures 1 and 2 comprise a pair of wires or rods 13 twisted together at their central portions with their ends extending angularly into the slabs 10 and 11 to be anchored therein. As shown, each wire makes one complete loop so that its opposite end por-

2

tions are imbedded in different slabs. The twisted central portions of the wires are preferably covered with yielding plastic material 14 such as rubber, asphalt composition, or the like to hold back the plastic concrete during setting and to compress when the slabs expand to permit their faces to move closer together.

With the device installed, as shown, any vertical load on one of the slabs will be transmitted through the wires 13 and through the twisted central portions thereof to the opposite slab to hold the upper surfaces of the slabs substantially in exact alignment at all times. When the slabs expand so that their faces tend to move together, the twisted portions of the wires tend to twist slightly and will flex to accommodate such movement, the material 14 compressing at this time. As the slabs contract so that their adjacent faces tend to separate, the twisted portions of the wires will bend to twist more tightly together. This operation will continue until the wires are tightened to the maximum extent at which time further separation of the slab faces will be prevented to prevent disengagement of the slab faces from the filler strip 12.

In the construction shown in Figure 3, the load transfer device is similarly formed by two wires 15 twisted together at their central portions and each having one and one-half loops so that the end portions of each wire are in the same slab. The twisted central portions are covered with yielding plastic material 16 to accommodate compression of the joint. Vertical loads will be transmitted through the wires and through the inter-twisted portions thereof to maintain the upper surfaces of the slabs in substantially the same plane while horizontal movement of the slabs will be accommodated by flexing of the twisted portions and compression of the material 16 in the same manner as described in connection with Figures 1 and 2.

In the construction shown in Figure 4, the load transfer device is formed by four wires, 17, 18, 19 and 20, all twisted together at their central portions and covered by yielding plastic material 21. The wires may be so twisted that the ends of each wire are imbedded in each slab or in different slabs as desired. This construction functions in substantially the same manner as the constructions of Figures 1 and 3, except that it can carry slightly greater loads due to the increased number of wires or rods employed.

Figures 5 and 6 illustrate a different type of load transfer device for connecting adjacent slabs 22 and 23 having a compressible filler strip 24

3

between their adjacent faces. The load transfer device is formed by a single strip or plate of sheet metal having its edge portions slit and bent out in opposite directions to form legs 25 to be imbedded and anchored in the slabs. The legs connect to the central portion 26 of the strip or plate which lies vertically between the slab faces. The central portion 26 is partially slit between the adjacent legs as indicated at 27. Preferably, the legs are bent in such a manner as to provide short horizontal bearing portions 28 next adjacent the central portion 26, as shown.

When this unit is installed in the slabs in the position shown in Figure 5 yielding strips 29 are placed between the opposite faces of the central portion 26 and the adjacent slab faces. Preferably, the strips 29 are secured to the opposite faces of the central portion 26 for convenience in handling.

Vertical loads between the slabs will be transferred through the legs 25 and the central portion 26 without permitting appreciable movement of the slabs relative to each other due to the relatively short parts of the legs which extend from the slab faces and the fact that such loads are transmitted vertically through the central portion 26. Upon expansion of the slabs, the central portion 26 of the plate will be distorted, this action being assisted by the slits 27 and by compression of the strips 29 to permit the slab faces to move closer together. When the slabs contract, the central portion 26 of the plate will distort in the opposite direction to permit the slab faces to separate. It will be noted, however, that distortion of the strip is limited so that the slab faces can separate only to a predetermined limited extent which is not sufficient to break the seal between the filler strip 24 and the slabs.

While several embodiments of the invention have been shown and described in detail, it will be understood that these are illustrative only and are not intended as a definition of the scope of the invention, reference being had for this purpose to the appended claims.

What is claimed is:

1. A load transfer device adapted to be imbedded in adjoining concrete slabs for transferring loads therebetween and for limiting separation thereof comprising a substantially vertically rigid and horizontally yieldable body portion having oppositely disposed legs extending outwardly and upwardly from the top of the body portion and oppositely disposed legs extending outwardly and downwardly from the bottom of the body portion, the legs on one side of the body portion adapted to be imbedded in one of the adjacent slabs and the legs on the other side of the body portion adapted to be imbedded in the other adjacent slab with the body portion vertically disposed therebetween for transferring vertical loads between the slabs, and a plastic material of substantial thickness about the body portion providing for limited horizontal yielding of the body portion and adapted to provide limited separation of the adjacent slabs.

2. A load transfer device adapted to be imbedded in adjoining concrete slabs for transferring loads therebetween and for limiting separation thereof comprising a plurality of elongated wires twisted together at their central portions to provide a substantially vertically rigid and horizontally yieldable body portion and with their end portions providing oppositely disposed wire legs extending outwardly and upwardly from the top of the twisted wire body portion and op-

4

positely disposed wire legs extending outwardly and downwardly from the bottom of the twisted wire body portion, the wire legs on one side of the twisted wire body portion adapted to be imbedded in one of the adjacent slabs and the wire legs on the other side of the twisted wire body portion adapted to be imbedded in the other adjacent slab with the twisted wire body portion vertically disposed therebetween for transferring vertical loads between the slabs, and a plastic material of substantial thickness about the twisted wire body portion providing for limiting horizontal yielding thereof and adapted to provide limited separation of the adjacent slabs.

3. A load transfer device adapted to be imbedded in adjoining concrete slabs for transferring loads therebetween and for limiting separation thereof comprising a plurality of elongated wires twisted together through substantially 360° at their central portions to provide a substantially vertically rigid and horizontally yieldable body portion and with their end portions providing oppositely disposed wire legs extending upwardly and outwardly from the top of the twisted wire body portion and oppositely disposed wire legs extending downwardly and outwardly from the bottom of the twisted wire body portion, the wire legs of each elongated wire extending from opposite sides of the twisted wire body portion, the wire legs on one side of the twisted wire body portion adapted to be imbedded in one of the adjacent slabs and the wire legs on the other side of the twisted wire body portion adapted to be imbedded in the other adjacent slab with the twisted wire body portion vertically disposed therebetween for transferring vertical loads between the slabs, and a plastic material of substantial thickness about the twisted wire body portion providing for limited horizontal yielding thereof and adapted to provide limited separation of the adjacent slabs.

4. A load transfer device adapted to be imbedded in adjoining concrete slabs for transferring loads therebetween and for limiting separation thereof comprising a plurality of elongated wires twisted together through substantially 450° at their central portions to provide a substantially vertically rigid and horizontally yieldable body portion and with their end portions providing oppositely disposed wire legs extending outwardly and downwardly from the bottom of the twisted wire body portion, the wire legs of each elongated wire extending from the same side of the twisted wire body portion, the wire legs on one side of the twisted wire body portion adapted to be imbedded in one of the adjacent slabs and the wire legs on the other side of the twisted wire body portion adapted to be imbedded in the other adjacent slab with the twisted wire body portion vertically disposed therebetween for transferring vertical loads between the slabs, and a plastic material of substantial thickness about the twisted wire body portion providing for limited horizontal yielding thereof and adapted to provide limited separation of the adjacent slabs.

5. A load transfer device adapted to be imbedded in adjoining concrete slabs for transferring loads therebetween and for limiting separation thereof comprising a sheet having its upper and lower edge portions slit to form tongues which are alternately bent outwardly in opposite directions to provide a substantially vertically

rigid and horizontally yieldable body portion and oppositely disposed legs extending outwardly and upwardly from the top of the body portion and oppositely disposed legs extending outwardly and downwardly from the bottom of the body portion, the legs on one side of the body portion adapted to be imbedded in one of the adjacent slabs and the legs on the other side of the body portion adapted to be imbedded in the other adjacent slab with the body portion vertically disposed therebetween for transferring vertical loads between the slabs, and a plastic material of substantial thickness about the body portion providing for limited horizontal yielding of the body portion and adapted to provide limited separation of the adjacent slabs.

6. In combination with a pair of adjoining concrete slabs, a load transfer device imbedded in the adjoining slabs and comprising a substantially vertically rigid and horizontally yieldable body portion having oppositely disposed legs extending outwardly and upwardly from the top of the body portion and oppositely disposed legs extending outwardly and downwardly from the bottom of the body portion, the legs on one side of the body portion being imbedded in one of the adjacent slabs and the legs on the other side of the body portion being imbedded in the other adjacent slab and the body portion being vertically disposed between the adjacent slabs for transferring vertical loads therebetween, and a plastic material

of substantial thickness about the body portion for spacing the body portion from the adjacent slabs to provide for limited horizontal yielding of the body portion and limited separation of the adjacent slabs.
